(57) **CLAIM**

The ornamental design for a screen mount device, as shown and described.

DESCRIPTION

FIG. 1 is a perspective view of a screen mount device showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view thereof, showing the screen mount device in an environment of use;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines shown in FIGS. 1, 4 and 5 illustrate portions of the screen mount device that form no part of the claimed design. The broken lines illustrating the hook connector in FIGS. 8-14 are environment that form no part of the claimed design, while the remaining broken lines in FIGS. 8-14 illustrate portions of the screen mount device that form no part of the claimed design.

1 Claim, 14 Drawing Sheets
